(57) CLAIM

The ornamental design for a watch case as shown and described.

DESCRIPTION

1. Watch case

1.1 : Perspective view 1

1.2 : Perspective view 2

1.3 : Front

1.4 : Left

1.5 : Right

1.6 : Back

1.7 : Top

1.8 : Bottom

The broken lines shown in the drawings depict portions of the watch case that form no part of the claimed design; The characteristic features of the design lie in the shape of the main body of the watch case; The product as a whole is used as a watch case; the use of the partial design is the main body of the watch case.
